(57) **CLAIM**

The ornamental design for a cranking cannon toy gun, as shown and described.

DESCRIPTION

FIG. 1 is a left side view of a cranking cannon toy gun showing our new design;

FIG. 2 is a right side view thereof;

FIG. 3 is a front elevation view thereof;

FIG. 4 is a rear elevation view thereof;

FIG. 5 is a top plan view thereof; and,

FIG. 6 is a bottom plan view thereof.

The broken lines represent the portions of the cranking cannon toy gun that form no part of the claimed design.
